ABSTRACT OF THE DISCLOSURE

Thickened hydrocarbon fluids obtained by the in situ reaction of a long chain amine and isocyanate to form urea, and method of use for drilling fluids, fracturing fluids, packer fluids, and the like in petroleum production operations.

BACKGROUND

It has been found desirable in field practice to use thickened hydrocarbon fluids as fracturing fluids, packer fluids, and drilling fluids. Many methods of forming such fluids are known to the art such as the use of soaps of fatty acids. Thickened oil systems are preferred for these uses, however, emulsions of the water-in-oil type, invert emulsions, have been found to be useful for drilling fluids. One serious disadvantage of the fatty acid soap method for thickening is the extensive mixing necessary to formulate the thickened hydrocarbon product. This is particularly undesirable in view of the fact that such compositions are generally formulated in the field where elaborate mixing or shearing equipment is not readily available.

One method used for increasing the flow of fluid through subterranean formations penetrated by the bore of a well involves liquid injection through the well bore into the well formation at hydrostatic pressures high enough to form a passage-way by fracturing the subterranean formation into which the liquid is injected. It can be seen that fractures may be formed by such hydraulic action, but such passage-ways must be held open to permit the desired fluid flow following fracture. The general practice is to convey into the subterranean formation together with the fracturing fluid a particulated material to act as a "propping" agent to physically hold such fractures open. Propping agents such as sand, aluminum beads, glass beads, walnut shells, and the like have been used. One of the greatest difficulties encountered in the use of fracturing fluids containing propping agents is maintaining the particulated solids suspended somewhat evenly in the liquid media used to hydraulically fracture the formation. A disadvantage of some presently used fracturing fluids, such as the thickened or viscous oils, is that the viscosity changes with temperature. That is, the fluid may be of a satisfactory consistency to maintain the propping material in an even suspension at ground level temperatures, but when subjected to higher temperatures in the well tubing and well formation, the viscosity is lowered permitting the propping agent to settle out of the fracturing fluid. Further, the storage stability of many presently used fracturing fluids containing propping agents is not satisfactory.

Corrosion of oil well casings has long been recognized as a serious problem in petroleum production. Various types of materials have been utilized to pack the annulus between the casing and the tubing and the annulus between the casing and the surrounding formation to inhibit corrosion. Presently used packer fluids include aqueous base compositions thickened with clays and containing additives such as weighting agents, corrosion inhibitors, and biocides, etc. Caustic is sometimes added to the packer fluid to inhibit the acidification of the packer compo-

2

sition while it is in place. Oil base packer fluids are preferred in view of their natural anti-corrosive properties. Many of the current compositions presently utilized are difficult to pump into a small annular space when they are sufficiently thick to evenly suspend additives, and those compositions which are readily pumpable due to their lower viscosity have the disadvantage of permitting additive materials to settle out and plug the lower end of the annular spaces. Further, it is desirable that the packer fluid be maintained in a state in which it may be readily removed from the annular areas to rework the well. In order to achieve this, a thixotropic material is necessary. A review article setting forth desirable properties for packer fluids is "Oil Mud Packs for Combating Casing Corrosion," Materials Protection, V. No. 6, June 1966, pp. 21-25. It is also very desirable to have a packer fluid which may be readily formulated at the well site, especially if it can be formulated from the fracturing or drilling fluid used at the same site.

20 The drilling of oil or gas wells is generally accomplished by a rotary drill having a hollow drill stem with a bit attached to its lower end. During the drilling, a fluid known as a drilling fluid is continuously circulated downward through the drill stem and bit, out against the working face of the hole, and then upwardly to the surface through the annular space between the drill stem and the wall of the bore hole. The drilling fluid serves to cool and lubricate the drill bit, suspend and remove cuttings from the hole, and prevent the flow of liquids or gasses from the formations into the bore by applying a positive pressure to the face of the formation. Both water base and oil base drilling fluids are presently utilized. Oil base or water-in-oil emulsion type fluids are preferred to reduce or prevent swelling of argillaceous materials in underground formations traversed by the well bore, to prevent sloughing when drilling through shale materials, and to prevent vaporization experienced in the use of water base compositions in hot wells. Further, many of the water-clay muds are expensive to maintain in good condition. Drilling fluids may also contain minor proportions of various compositions to impart special properties to the composition, such as wall-building agents, weighting agents, dispersing agents, viscosity modifiers, corrosion inhibitors, etc. Some disadvantages of the presently used drilling fluids include the wide range of viscosities experienced with the normal variations of temperatures encountered in oil well operations, the inability of the generally used oil base systems to tolerate water, and the requirement of special mixing equipment at the oil well site to formulate the drilling fluid from presently used amine reacted clays, etc.

SUMMARY OF THE INVENTION

This invention is directed toward a composition and method to obviate many of the disadvantages experienced with prior art materials. This invention provides a composition which may be used as a drilling fluid, packer fluid or fracturing fluid, and which may be readily formulated at the well site without requiring elaborate mixing equipment. The thixotropic hydrocarbon oil base composition of our invention comprises a major proportion of hydrocarbon oil and a minor proportion of urea produced by the in situ reaction of an aliphatic amine and an isocyanate selected from the group consisting of aromatic and aliphatic mono- and polyisocyanates. Mixtures of amines and mono- and polyisocyanates may be used. The amine terminated structure is preferred.

Aliphatic amino compounds are preferred amine reactants, particularly amines containing an aliphatic group of from about 6 to 22 carbon atoms attached to an amino nitrogen. Such aliphatic groups may be a branched or straight hydrocarbon chain and saturated or unsaturated.

Primary mono-amines selected from the group consisting of N-normal-alkyl, N-normal-alkenyl and N-secondary-alkyl amines having from about 6 to 22 carbon atoms are preferred. N-secondary-alkyl amines are especially useful due to their low melting points resulting in amines having fluid properties under field conditions. One preferred subclass is N-secondary-alkyl amines having from about 7 to 18 carbon atoms. The aliphatic group may be a cyclic group or an arylalkyl group such as 9,10-phenylstearylamine as derived from oleic acid.

Isocyanates suitable for the process of this invention include those isocyanates which react with an amine to form a urea. Long chain aliphatic isocyanates are suitable wherein the aliphatic group contains from about 6 to 22 carbon atoms. It is preferred to use difunctional isocyanates, or pre-polymers thereof, including diisocyanates such as toluene diisocyanate, hexamethylene diisocyanate, and the long chain aliphatic diisocyanates such as derived from aminostearyl amine and aminomethylstearylamine.

Suitable hydrocarbon oils for use in the composition of this invention include crude petroleum, petroleum distillates such as kerosene and fuel oil, residual oils, or a blend of crude and refined oils.

The compositions of this invention may be readily formulated by simple mixing of the amine and isocyanate reactants in the hydrocarbon oil to form urea in situ. It is preferred to add the amine to the oil first and then add the isocyanate with stirring. To form the ureas, it is suitable to use from the stoichiometric requirement of amine and isocyanate to about 40 percent excess of amine. That is, the mole ratio of amine to diisocyanate may range from about 2:1 to 2.8:1.

The compositions of this invention may be formulated in batches by simple mixing in tanks, adding desirable additive agents such as corrosion inhibitors, biocides, propelling agents, weighting agents, etc. with stirring and stored for use as desired. Such compositions are stable over wide temperature ranges and over long periods of time.

The compositions of this invention are especially well suited for continuous production such as may be desired in the case of fracturing and drilling fluids. The urea may be formed on a continuous basis in the pipe leading to the well bore by simply introducing the appropriate quantities of amine and isocyanate to the hydrocarbon oil flow in the pipe. Desired additive agents may be introduced toward the well head down line from the introduction of amine and isocyanate so that such agents will be adequately and evenly suspended in the thickened fluid.

Suitable compositions according to this invention may be formulated using from about 0.05 to 2 weight percent urea concentration in the oil. Preferred compounds contain from about 0.1 to 1.0 weight percent urea. The optimum concentration of urea will vary depending upon the type of hydrocarbon utilized and the particular thickening properties desired.

The thickened hydrocarbon compositions of this invention are readily emulsified for use in aqueous systems

using conventional emulsifiers and well known emulsion techniques.

Compositions may be formulated according to this invention to a wide range of viscosities to suspend evenly 5 and for long periods of time various suitable additive agents such as weighting materials, propelling agents, corrosion inhibitors, biocides, etc., and to maintain even suspension of such materials over wide variations of temperature. Further, the compositions of this invention exhibit desirable thixotropic properties which enables them 10 to be pumped into narrow annular spacings while at the same time furnishing sufficient body to maintain suspension of materials over wide annular spacings when the materials are used as packer fluids. The thixotropic properties of the compounds of this invention also permit packer fluid which has been in place for long periods of 15 time to be readily removed from the casing for remedial work in the well bore. The urea containing compositions of this invention are particularly well suited for use as a packer fluid where the composition remains in the annular space for several years, since the urea will not decompose into undesirable chemicals such as acids, etc. The compounds of this invention are especially useful as 20 drilling fluids and fracturing fluids by virtue of their capability to evenly suspend desirable additives, provide adequate suspension for removal of cuttings and the like, and at the same time not produce deleterious effects to the oil bearing formation. The thickened compositions of this 25 invention also will tolerate relatively large amounts of water.

One advantage of the composition of this invention is its ease of formulation by simple mixing which may be readily carried out at the well site without the requirement of elaborate equipment. A further advantage is the 30 continuous method of formulation possible directly in the hydrocarbon oil flow to the well head. Still another advantage is the use of one basic thickened oil base fluid which may be adapted for use as a drilling fluid, packer fluid, or fracturing fluid in petroleum operations by the simple addition of desired additives for the particular use.

The following examples are presented to illustrate the present invention.

EXAMPLE I

Mid-Continent crude oil was thickened by the in situ reaction of N-sec-alkyl primary amine and toluene diisocyanate. The crude oil was added to a beaker and an amine was added directly to the crude oil with stirring in an amount to produce the concentration and mole ratio noted in Tables I and II, following which toluene diisocyanate was added to produce the concentration and mole ratio noted. The stirring was continued until maximum thickening was obtained, usually a matter of minutes. The viscosity was obtained by measurement with a Brookfield Viscometer at the temperatures and revolutions per minute noted in Tables I and II. Round spindles were used for all viscosity determinations.

¹ Amine plus toluene diisocyanate.

13
EXAMPLE VIII

The procedure of Example I was followed using N-sec-alkyl(C₁₅₋₂₀) primary amines and diphenylmethylenec 4,4'-diisocyanate in kerosene at the concentration and mole ratios noted in Table XIV. The thickened oil compositions exhibited viscosities set forth in Table XIV.

14

cording to the procedure of Example I using toluene diisocyanate and the amine noted in Table XV. The concentrations and mole ratios are shown in Table XV.
⁵ Kerosene and water were added to the thickened product

¹ Mole ratio of above amine to diisocyanate is 2:1.

² Mole ratio of above amine to diisocyanate is 2.4:1.

EXAMPLE XI

Drilling fluid may be prepared by adding 1 pound of N-sec-alkyl(C_{11-14}) amine to 1 barrel of residual fuel oil cutback with #2 fuel oil (60-40 percent) followed by the addition of 0.42 pound of toluene diisocyanate and stirring to form urea in situ thereby thickening the oil composition. Following formation of the urea, a weighting agent or other desired additive may be added as desired depending upon well conditions.

EXAMPLE XII

A packer fluid may be prepared by adding 1.1 pounds of N-sec-alkyl(C_{15-20}) amine to 1 barrel of Mid-Continent crude oil followed by the addition of 0.3 pound of toluene diisocyanate with stirring to form urea in situ in the crude oil. Following formation of the urea, N-tallow trimethyl-enediamine dioleate may be added as a corrosion inhibitor

hand stirring to form urea in situ. Eighty-four pounds of Ottawa sand of about 12-20 mesh particles size is added to the thickened oil to serve as a propping agent. The fracturing fluid containing the propping agent may then be pumped into the well under pressure to effect the fracture of subterranean formations and to maintain the fractured fissures open to the flow of petroleum liquids.

EXAMPLE XIV

Kerosene and #2 fuel oil compositions were thickened, following the method of Example I, by the in situ formation of urea resulting from reaction of toluene diisocyanate and the amine at the mole ratios and concentrations noted in Table XVII. The thickened fluids were allowed to stand at room temperature for 15 minutes in 300 milliliter graduated cylinders. Then a grain of 20 mesh sand was dropped into the cylinder and the time recorded for the sand grain

to drop through 12 inches of the thickened fluid. In especially suitable fracturing fluids, 20 mesh sand will fall less than 1 foot per minute. Table XVII records the rates of fall observed.

to 2 weight percent of di-substituted urea produced by the in situ reaction of an unsubstituted aliphatic primary mono-amine having about 6 to 22 carbon atoms in a hydrocarbon aliphatic group attached to the amino nitrogen and a

¹ Molar ratio of above amines to diphenylmethylene 4,4'-diisocyanate is 2:1.

² Molar ratio of above amines to diphenylmethylene 4,4'-diisocyanate is 2.4:1.

While in the foregoing specification this invention has been described in relation to certain preferred embodiments thereof, and many details have been set forth for purpose of illustration, it will be apparent to those skilled in the art that the invention is susceptible to additional embodiments and that certain of the details described herein can be varied considerably without departing from the basic principles of the invention.

We claim:

1. A thixotropic hydrocarbon oil base composition comprising a major portion of hydrocarbon oil and about 0.05

65 urea and said amine being added in the mole ratio of amine to diisocyanate of from 2:1 to 2.8:1.

2. The composition of claim 1 wherein said amine is selected from the group consisting of N-normal-alkyl, N-normal-alkenyl, and N-secondary-alkyl amines having from about 6 to 22 carbon atoms.

3. The composition of claim 1 wherein said amine is N-secondary-alkyl amine having from about 7 to 18 carbon atoms.

4. The composition of claim 1 wherein said diisocyanate is toluene diisocyanate.

19

5. The composition of claim 1 wherein from about 0.1 to 1.0 weight percent in situ formed urea is present.

6. The composition of claim 1 wherein said amine is N-secondary-alkyl amine and said diisocyanate is toluene diisocyanate.
